UNITED STATES PATENT OFFICE.

VICTOR KOBLER, OF RORSCHACH, SWITZERLAND, ASSIGNOR TO THE FIRM OF ADOLPH SAURER, OF ARBON, WEITEGASSE, SWITZERLAND.

EMBROIDERING-MACHINE.

No. 824,725.

Specification of Letters Patent.

Patented July 3, 1906.

Application filed June 19, 1905. Serial No. 265,915.

To all whom it may concern:

Be it known that I, VICTOR KOBLER, a citizen of the Republic of Switzerland, residing at Rorschach, in Switzerland, have invented 5 new and useful Improvements in Embroidering-Machines, of which the following is a specification.

The object of the present invention is a frame suspension for embroidering-machines 10 in which all of the supporting-bearings of the counterbalancing-gear for carrying and balancing the frame with the mounted fabric are secured to the most stable parts of the machine—the main side supports.

15 As the perfect manufacture of the fabric is dependent upon the vibrationless and steady operation of the frame, it is obviously of the greatest importance to keep away as much as possible the vibrations of the machine 20 from the fabric-frame. This I attain by thus disposing the bearings journaling the supporting-gear in relation to the main supports that they exert their vertical pressure within these most stable parts of the machine.

25 Heretofore the fabric-frame and the counterbalancing-weights have been suspended by means of segments or levers to longitudinal or cross shafts, using several journals at various vibrating points more or less distantly 30 located from the main supports. As a consequence these bearings vibrating with their points of attachment, the manufacture of good fabric was seriously interfered with.

35 In my improved construction I pivot two levers to the main supports, one at either side of the fabric-frame, in such a manner that their free ends, which operate the frame, are directed toward one another for the purpose of counterbalancing the side pressures 40 caused upon the fabric-frame traveling vertically up or down by the friction between these lever-arms and the frame.

45 In order to make the invention more readily understood, I will now describe it with reference to the accompanying drawing, which represents a front view of one form of my invention, parts of the machine having no bearing on this invention having been omitted.

50 In the drawing, *a* represents the fabric-frame. *b* and *k* are the main side supports. The vertical middle planes containing the longitudinal axis of the bearings *p* and *q* co-

incide with the vertical middle plane of the respective supports *b* and *k*. The free end of the rocking lever *c*, journaled at *p*, carries a roller *d* and slides therewith in the slot *f* of the frame *a*. To the other end is pivotally suspended the weight *h* by means of the rod *g*, the lower end of which in turn is pivoted 60 to the bell-crank lever *i*, fulcrumed to the support *b*. The free end of the rocking lever *l* carries a roller *m* and engages therewith the slot *n* in the frame *a*. The lower arm of this rocking lever, which latter is pivoted at *q* to 65 the support *k*, is jointed to the other rocking lever *i* by means of the rod *o*. In this construction the equilibrium of the frame and counterweight is assured in any position of the frame. Upon the frame ascending the 70 friction of roller *d* in slot *f* causes a slight side pressure upon the frame, which pressure, however, is offset by the corresponding side pressure exerted by roller *m* in slot *n*. By this means a vertical frame movement is as- 75 sured which is absolutely free from vibration.

Having now particularly described and ascertained the nature of the said invention and in what manner the same is to be performed, I declare that what I claim is— 80

1. In an embroidering-machine, the combination with the supports, of a fabric-frame mounted between the latter and having longitudinally-arranged slots therein, a lever on each support, the free ends of the levers being directed toward each other and the center of the frame, bearing-rollers on the free ends of the levers traveling in said slots, and counterbalancing means connected to said levers. 90

2. In an embroidering-machine, the combination with two supporting members, of a fabric-frame mounted between the latter and having longitudinally-arranged slots therein, a lever fulcrumed on each support, the free ends of the levers being directed toward each other and the frame, a roller journaled in the free end of each lever adapted to travel in said slots, and counterbalancing means connected to the power end of each lever. 95

3. In an embroidering-machine, the combination with two supporting members, of a fabric-frame mounted between the latter, a straight lever fulcrumed on one of the supports and a bell-crank lever fulcrumed on the other, one of the ends of each of said levers 100

directed toward each other and slidably connected to the frame, a second bell-crank lever pivoted to the support carrying the straight lever, a rod connecting the two bell-crank levers and a weighted rod connecting the two levers mounted on the same support, substantially as and for the purposes set forth.

In testimony whereof I have signed my name to this specification in the presence of two subscribing witnesses.

VICTOR KOBLER.
